UNITED STATES PATENT OFFICE

134,721

DESIGN FOR A DISPLAY STAND FOR CARTONS, CONTAINERS, OR THE LIKE

Maximilian C. Meyer, Brooklyn, N. Y.

Application September 11, 1940, Serial No. 94,931

Term of patent 3½ years

To all whom it may concern:

Be it known that I, Maximilian C. Meyer, a citizen of the United States, residing at Brooklyn, in the county of Kings and State of New York, have invented a new, original, and ornamental Design for a Display Stand for Cartons, Containers, or the like, of which the following is a specification, reference being had to the accompanying drawing, forming a part thereof.

The figure is a perspective view of the display stand for cartons, containers, or the like, showing my new design.

The dominant feature of the design resides in the portions of the display stand shown in full lines.

I claim:

The ornamental design for a display stand for cartons, containers, or the like, as shown and described.

MAXIMILIAN C. MEYER.
